UNITED STATES PATENT OFFICE.

JOHN P. STORMS, OF ENID, OKLAHOMA.

DOOR.

Application filed August 5, 1921. Serial No. 490,042.

To all whom it may concern:

Be it known that I, JOHN P. STORMS, a citizen of the United States of America, and resident of Enid, in the county of Garfield and State of Oklahoma, have invented certain new and useful Improvements in Doors, of which the following is a specification.

This invention relates to flexible doors, and particularly to doors of this type which are moved upward to open the doorway and in which a flexible and variable counter balancing mechanism is employed which aids in the operation of the door and serves to retain it in different positions, either open or partially open.

An object of this invention is to provide a door of the character indicated in which a flexible counter balancing mechanism may be located at a point remote from the door, the flexible counter balancing mechanism being connected to the door at one end and the other end being connected to a fixed part or support, so that the counter weight will have variable points of flexure to accord with the position of the door.

It is furthermore an object of this invention to produce a door which will operate without the application of undue force, since provision is made for reducing the friction and facilitating its operation.

It is a still further object of this invention to produce a door having a counter weight in which the mechanism employed is comparatively simple and inexpensive.

A still further object of this invention is to produce novel means whereby the weights are held in operative relation to the mechanism to prevent the weights becoming entangled with the chain or support to which they are connected, provision being also made to relieve the weight on the cable or element to which the weights are connected, under certain conditions of use.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a sectional view of

a building, showing a door embodying the invention applied thereto;

Figure 2 illustrates a sectional view on the line 2—2 of Fig. 1;

Figure 3 illustrates a top plan view of the door and its supports with the guides in section;

Figure 4 illustrates an enlarged detailed view of the weights and parts associated with them; and

Figure 5 illustrates a sectional view through a fragment of the door, showing a guide in section.

In these drawings 10 denotes the building to which the door is applied, the said door comprising a plurality of horizontally disposed slats 11, the interengaging edges of which are preferably shaped to form interlocking joints. The slats are held in assembled relation to each other by flexible elements 12 which are secured to the backs of the slats to permit the slats to move with relation to each other. These flexible elements may be of leather, webbing or other material effective to hold the slats in assembled relation to each other, as stated, and the said flexible members or some of them are guided over rollers 13 rotatably mounted in connection with a shaft 14 at the top of the doorway.

The door frame is usually provided with guide strips 15 which are spaced to provide a recess in which the ends of the slats may slide to provide a way, the outer strip being curved opposite the roller.

Rails 16 have their ends supported above the door opening, and these rails extend rearwardly and preferably upwardly slightly and terminate near the rear of the structure, in the present embodiment of the invention. The rails are either spaced apart or they may be grooved as shown at 17, to receive carriers for anti-friction rollers 18 which have appropriate journals to support the door as it moves rearwardly over the rails 16, two of the flexible members 12 preferably engaging the anti-friction rollers, as shown in Figure 2.

A flexible yoke 19 has its ends connected to two of the flexible members at the top of the door, and the said yoke is connected to a cable 20 which operates over a pulley or sheave 21 on a shaft 22 which is supported at the rear of the rails. The cable terminates just beyond the sheave or pulley 21.

when the door is in closed position, and it is intended that the end of the cable shall descend as the door is elevated.

As a means for counter balancing the weight of the door, a flexible element such as a chain 23 forms a continuation of the cable, and a portion of this chain may be formed of a series of weighted links 24, the weight of the links depending upon the size of the weight of the door, and they should be of such size as to counterbalance the weight of the door without overcoming the friction attending the operation of the door. It is the purpose of the inventor that manual power shall be applied to overcome the friction, otherwise the door would be held open by the weights. As shown in Figure 4 of the drawing, the lower end of the chain 23 is preferably anchored as at 25 above the floor of the structure, in order that one end of the flexibly connected links 24, which form a counter weight that exerts a variable pull upon the flexible door as a portion of the chain-like weight will hang vertically from the anchorage 25 for a portion of its length when the door is raised.

The weight of the chain at one end is carried on the anchor member 25 when the door is open, thus relieving the cable of such weight and permitting the door to be pulled to a closed position with little or no force. It will also be observed that when the door is closed, the weight of the chain will permit the door to be opened with the application of very little power, and when the door is pulled from an open to a closed position, the weighted links are gradually removed from the anchor to the cable whereas the reverse action occurs when the door is being opened. This results in balancing the weight of the links during the manipulation of the door.

The structure shown embodies a flexible and vertically slidable door which when raised moves upon rearward and upward inclined rails or supports maintained at an inclination and adapted to carry the weight of that portion of the door which contacts with the supports or with the rollers carried thereby, the counter balancing weight is connected to the door by appropriate flexible connections to which the flexible counter balancing weights are attached, so that one end of the series of weights will hang from a guide roller, the other end of the weights engaging at a suitable elevation a fixed support or fastening 25. The structure organized as shown or in any other appropriate manner to embody the means set forth or equivalents thereof provides a vertically movable articulated door, a support for such door which will carry the entire or a portion of the weight of the door, and an automatically variable counter weight the gravity pull thereof operating

upon the door and changing relative thereto in accord and under control as to the position of the door, so in use the pull of the weight upon the door will decrease in proportion to its vertical position. One end 70 of the counter-balancing weight being fixedly maintained and the other end being vertically movable provides a loop or catenary which is variable or changeable vertically, effecting when the door is in its lowest 75 position, the greatest pull upon the door, the force of the pull diminishing as the door is raised, and the weight thereof is transferred to the supports and in accord with such movement of the door or closure 80 a proportion of the weight of the flexible counter-weight will be carried by the fixed support, and thus the amount of pull upon the door will vary in accord with the vertically movable point of suspension that accords with the pull of the door downward less the weight of the door carried by the supports.

This improvement in door operating means is particularly adapted for garage 90 use or like buildings, where it is desirable to keep the entire floor clear and to provide in such a structure, means whereby the manual effort to open and close the doorway may be varied at the start of the opening 95 or closing by changing the effective length of the counterbalancing linked weight. In use, the rearward and upward inclined supports are engaged by an intermediate portion of the door and the flexible connection 100 between the door and the weight is between the inclined supports.

I claim—

1. In a flexible door, slats forming the door, flexible elements attached to the slats 105 for holding them in assembled relation to one another, vertical guides for the said door for engagement with the ends of the slats, pairs of rails which extend inwardly and lengthwise of the structure upwardly from 110 the door opening, anti-friction rollers between each pair of rails which extend above the rails to be engaged by the door, a yoke with diverging ends which are connected to the door, a cable attached to the converging 115 ends of the yoke and extending rearwardly therefrom, a pulley centrally located adjacent to the rear wall of the structure over which the cable travels, a flexible and vertically movable weighted element forming a 120 continuation of the cable, and means for anchoring and suspending the weighted element at the end remote from its connection with the cable.

2. In a flexible door, slats, flexible elements extending transversely of the slats and secured thereto, rails extending rearwardly and upwardly from the door opening, pulleys at the outer ends of the rails over which the door is guided to the rails, 125

anti-friction elements on the said rails, a cable connected to the door, a pulley over which the cable operates, a flexible counter weight having one end attached to the cable 5 to be vertically movable, and means for maintaining the other end of said flexible counter weight in a fixed position, whereby the counter weight will have its catenary vertically movable to accord with the position of the door.

3. In a flexible door, slats having guiding means, flexible elements connecting the said slats, a pair of intermediately positioned rails extending inwardly and upwardly 15 from the door, means for guiding the door to the said rails, a cable connected to the door, a pulley over which the cable may travel, a chain-like counter weight connected at one end to the said cable, and means 20 for anchoring the opposite end of the counter weight in fixed position above the floor of the building.

4. An articulated vertically movable door, supports which incline upward and rearward from a point above and rearward of the doorway for maintaining the door when raised, a flexible counter weight connected at one end with the door, means for maintaining the opposite end of said counter

weight in looped formation with a fixed point of suspension, to provide a variable pull upon the door which accords with its position upon the inclined supports. 30

5. In combination with an articulated vertically movable door and inclined ways for supporting such door when raised, of counter balancing means for the door comprising a flexible counterweight and a suitably guided connection attached to the door and to said flexible counter weight, one end of 40 said counterweight being maintained to provide a vertically movable point of suspension, the other end engaging means to provide a fixed point of suspension, both points of suspension being positioned to jointly 45 carry the entire weight of the flexible counter weight.

6. In combination with a vertically movable articulated door, rearward and upward inclined means for supporting the door or 50 a part thereof when raised, of a flexible counter weight for the door having a movable point of suspension which varies in accord with the position of the door and a fixed point of suspension organized to provide for a variable pull upon the door to 55 accord with the position of the door.

JOHN P. STORMS.
